[57] CLAIM

The ornamental design for a lightning deterrent, as shown and described.

DESCRIPTION

FIG. 1 is a front elevational view of a lightning deterrent showing my new design;

FIG. 2 is a rear elevational view thereof;

FIG. 3 is a top plan view thereof;

FIG. 4 is a bottom plan view thereof;

FIG. 5 is a side elevational view thereof;

FIG. 6 is a cross-sectional view taken through the line 6—6 of FIG. 1; and,

FIG. 7 is a front elevational view of a second embodiment thereof, wherein the only differences reside in the double slot opens and the length of the claimed design.

*Fig. 1**Fig. 2**Fig. 3**Fig. 4**Fig. 5**Fig. 7**Fig. 6*
